UNITED STATES PATENT OFFICE

ALBERT P. BALL, OF ROYAL OAK, AND FREDERICK ZENKER, OF HIGHLAND PARK,
MICHIGAN, ASSIGNEES TO DETROIT FUSE & MANUFACTURING COMPANY, A
CORPORATION OF MICHIGAN.

ELECTRICAL SWITCH.

1,291,667.

Specification of Letters Patent. Patented Jan. 14, 1919.

Application filed June 24, 1916. Serial No. 105,565.

To all whom it may concern:

Be it known that we, ALBERT P. BALL, a citizen of the United States, residing at Royal Oak, in the county of Oakland and State of Michigan, and FREDERICK ZENKER, a subject of the Emperor of Germany, residing at Highland Park, county of Wayne, and State of Michigan, have invented certain new and useful Improvements in Electrical Switches, of which the following, taken in connection with the accompanying sheet of drawings, is a full, clear, and concise description thereof.

Our present invention more particularly relates to motor starting switches of the type disclosed in a previous application filed by one Bryson Dexter Horton and ourselves on March 4, 1916, bearing Serial Number 82,197, upon which this present invention is an improvement.

In this previous application we have disclosed a motor starting switch in which novel means is shown for controlling the operation of the switch mechanism in such a way as to insure the initial closing of the switch in the starting position preparatory to closing it in its service or running position.

Among the objects of our present invention is to provide an improved form of controlling mechanism for this purpose of simplified character and one which is efficient in operation and of durable construction.

A further object of our present invention is to provide means whereby the movably-mounted switch contacts will be automatically thrown from starting to running position with that desirable rapidity which is necessary to render functionally inoperative the controlling mechanism which requires that the movable contacts be initially moved to the starting position before they can be thrown to the running position. These and other objects of the invention will be apparent from the following description, reference being had to the accompanying sheet of drawings in which we have shown by way of example a double throw switch embodying the principles of our present invention, and in which,—

Figure 1 is a view in top plan of such double throw motor starting switch, the

switch contacts being illustrated in running position;

Fig. 2 is an enlarged fragmentary view in side elevation of the switch controlling mechanism taken on line *a—a* of Fig. 1.

Fig. 3 is a similar view thereof showing the relative positions of the controlling latch and the operating crank when the contacts are in starting position as well as in neutral position, the latter being illustrated in dotted outline.

Generally describing the present invention in detail the switch mechanism is preferably housed within a rectangular metallic casing 1, provided with a hinged cover 2. This metallic housing serves as a protection to the switch mechanism as well as providing a convenient bearing support for the crank or operating member. In order to allow for the oscillatory movement of the crank when manipulated the cover is formed with an enlargement provided with the cavity 3. Mounted within the casing and upon the bottom thereof is the base 4, which may be made of suitable insulating material which serves as a mounting for the fuse holders 5 and the series of stationary contacts 6 and 7, the former representing the running contacts while the latter represents the starting contacts of the double-throw motor starter switch illustrated. Arranged intermediate of the contacts and likewise mounted upon the base 4 are the pivot supports 8 for the movable knife-blade contacts 9. These knife-blade contacts are cross-connected with each other by means of the connecting member or cross-head comprising a portion of the operating crank 10 and insulated therefrom by the sleeve of insulating material 11, suitable connectors 12 being employed for conveniently connecting the knife-blades to the insulated crank. The ends of the operating crank are journaled in opposite sides of the casing at a point substantially in alignment with the pivot points of movable knife-blade contacts. For the purpose of cheapness and convenient assembly the crank is of one-piece construction, and terminates in an outwardly and laterally-directed arm 13 which has fastened thereto a handle 14, by means of which the switch is manipulated.

From the description thus far it will be apparent that the crank which carries the knife-blade contacts is capable of being operated and made to assume two extreme and separated positions. That is to say, the knife-blade contacts may be brought into relation with the stationary running contacts 6, as illustrated in Fig. 1, or into co-operation with the starting contacts 7, as 10 illustrated in Fig. 3. An intermediate position of the crank 10, that is to say, the "off" position of the switch will be a position where the knife-blade contacts extend upwardly and substantially removed from 15 either set of stationary contacts.

In order to control the movement of the crank so as to prevent the knife-blade contacts from being thrown from neutral to running position but allowing the same to be initially thrown to starting position, and thereafter brought into running position, we provide the novel form of controlling mechanism illustrated in enlarged detail in Figs. 1 and 3. This particular mechanism which 20 we have illustrated by way of example takes the form of a forked controlling plate 15, pivoted at 16 to a standard or support 17, the latter being riveted at 18 to the bottom of the metal housing 1. This forked controlling plate is made of sheet metal and has two tangs 18^a and 19 between which are the stepped reëntrant apertures or cutouts 20 and 21, the lower ends of which conform in curvature to the curvature of the operating 25 crank. The guide walls of these reëntrant portions are slightly diverging to facilitate the operation of the crank when being thrown from one position to another.

The operating crank, it will be seen, is confined within and between the forked controlling plate. A spring 22 fast at one end to the standard 17 and at the other end to the forked controlling latch normally tends to hold the controlling latch in its upward 30 position where it normally coöperates with the crank when in off position to prevent the latter from being thrown directly to running position, as illustrated in dotted outline in Fig. 3. It will be noted that the 35 crank 10 is situated within the reëntrant cutout 21, and, by reason of the relation of the pivot points of the crank 10 and the latch 15, the crank is restrained and prevented from being moved to the running 40 position. However, the mounting of this latch plate in the manner described does not prevent the operating crank and connected knife-blade contacts from being thrown to the starting position. When such movement 45 is desired, the crank is operated, and during the operation it rides along the inner surface of the tang 19 of the latch, causing it to move on its pivot 16. In this manner the knife-blade contacts are brought into connection with the stationary starting contacts, 50

as will be apparent. When the spring 16 has passed over its dead center, the controlling latch will be caused to move to position shown in Fig. 3 with the tang 18^a resting against the crank, in position to be moved 70 when the crank is moved to throw the pivoted knife-blade contacts to running position, as will now be explained.

In motor starter switches it is desirable to make these movements sequential and the 75 latter movement from the starting position to the running position with great rapidity. We, therefore, have provided for this by employing a spring 23, under the tension of which this movement is automatically accomplished in a rapid manner. This spring at one end is anchored at 24 to the bottom of the casing 1 and has its other and free end curved or bent at 25 so as to partly encircle the crank, the intermediate portion of 80 the spring being coiled around the crank as shown in Fig. 1. It will be apparent from this that, after the crank is thrown over into starting position, tension will be put upon the spring 23 and it is this tension which, 85 when the crank is released by the hand of the user, automatically throws the movable knife-blade contacts from the starting contacts over on to the running contacts. The parts of the latch mechanism described are 90 so proportioned, and the movement thereof under the tension of the spring 22 is such that the movement of the crank from starting to running position under the tension of the spring 23 is effected before the latch 95 mechanism is enabled to arrest the movement of the crank by catching it in the reëntrant portion 21. When in this running position the crank 10 is accommodated within the reëntrant portion of the cutout 20, 100 as shown in Fig. 2. When the switch mechanism is again moved to break the circuit, that is, in throwing the switch to its "off" position, the latch 15 under the tension of the spring 22, causes the step formed by the 105 reëntrant or cutout 21 to pass beneath the crank 10 into controlling position, where it will prevent it from being thrown into running position without first having been initially moved to the starting position. 110

While we have illustrated one embodiment of our invention we do this by way of example to show one useful application of the principles involved, and by so doing, we do not wish to be understood as restricting ourselves to the precise structural details as these may be changed or altered without departing from the spirit and scope of our invention as defined by the following claims. 115

Having thus described our invention 120 what we claim as new herein and desire to secure by Letters Patent is:

1. In a device of the class described, the combination with a crank having a cross member, stationary running contacts at one 125

limit of movement of the crank, stationary starting contacts at the other limit of movement of the crank, movable contacts connected to said cross member and operable to be brought into engagement with either of said sets of stationary contacts, means for straining said crank toward the running contacts, a latch having a seat to anchor said crank in neutral position, and a toggle 5 acting spring operating to strain said latch to either side of its neutral position, according to the position of the latch, said spring when straining said latch toward said starting contacts permitting the free movement of said crank to be swung therefrom over to the running contacts.

2. In a device of the class described, the combination with a crank having a cross member, stationary running contacts at one limit of movement of the crank, stationary starting contacts at the other limit of movement of the crank, movable contacts connected to said cross member and operable to be brought into engagement with either of said sets of stationary contacts, means for straining said crank toward the running contacts, a latch having a seat to anchor said crank in neutral position, and a toggle acting spring operating to strain 10 said latch to either side of its neutral position, according to the position of the latch, said spring when straining said latch toward said starting contacts permitting the free movement of said crank to be swung therefrom over to the running contacts, said spring when straining said latch toward said running contacts coöperating with said straining means to anchor said crank in said seat.

3. In a device of the class described, the combination with a crank operable to swing either from neutral to the right or from right to left, a latch mounted to rock with said crank, a first means for normally straining said crank in the left direction of movement, a second means for normally straining said latch to the left or right limit of movement on either side of its neutral position according to the position of the latch relative to its neutral position, and means on said latch to anchor said crank in neutral position when said latch is strained in the left direction.

4. In a device of the class described, the combination with a crank operable to swing either from neutral to the right or from right to left, a latch mounted to rock with said crank, a first means for normally straining said crank in the left direction of movement, a second means for normally straining said latch to the left or right limit of movement on either side of its neutral position according to the position of the latch relative to its neutral position, said latch permitting the free movement of said crank to

the left from right to left when said latch is strained in the right direction, and means on said latch to anchor said crank in neutral position when said latch is strained in the left direction.

5. In a device of the class described, the combination with a crank having a cross member operable to swing from neutral to right and from right to left, a latch plate 70 coöperating with said crank pivotally mounted to rock with said crank and disposed in a plane perpendicular to said cross member, means for normally straining said crank in the left direction, means on said latch plate for anchoring said crank in neutral position, and means for rendering said anchoring means inoperative when said crank is swung from the extreme right to the left.

6. In a device of the class described, the combination with a crank operable to swing from neutral to right and from right to left, a latch mounted to rock with said crank, a first means for straining said crank in the left direction of movement, means on said latch for anchoring said crank in neutral position, and a second means for straining said latch in the right direction of movement when said crank is first swung to the right thereby permitting the free movement 80 of said crank from right to left.

7. In a device of the class described, the combination with a crank operable to swing from neutral to right and from right to left, a latch mounted to rock with said crank, said latch having a bifurcation with which said crank coöperates, a step on the right side of the bifurcation to arrest said crank in neutral position, a first means for normally straining said crank in the left direction of movement, and a second means for straining said latch in the right direction of movement when said crank is first swung to the right, thereby rendering said stop 90 ineffective and permitting the free movement of said crank from right to left.

8. In a motor starting switch having stationary starting and running contact members and coöperative movable contact members, the combination of means controlling the sequence of operations of said switch, and automatic means for quickly throwing said switch from starting to running position.

9. In a motor starting switch having stationary starting and running contact members and coöperative movable contact members, the combination of means controlling the sequence of operations of said switch and allowing only a rapid motion of the 115 movable contact members from starting to running position, and automatic means for quickly throwing said switch from starting to running position.

10. In a motor starting switch having sta- 120

- tionary starting and running contact members, the combination of means controlling the sequence of operations of said switch and allowing only a rapid motion of the 5 movable contact members from starting to running position, comprising a one-piece spring tensioned member, and automatic means for quickly throwing said switch from starting to running position.
10. 11. In a motor starting switch having starting and running positions, the combination of means controlling the sequence of operations of said switch, comprising a one-piece member spring tensioned so as to inherently tend to remain in either of two extreme positions, and automatic means for throwing said switch from starting to running position.
12. In a motor starting switch having stationary starting and running contact members and coöperating movable contact members, the combination of means controlling the sequence of operations of said switch, comprising a one-piece member spring tensioned so as to inherently tend to remain in either of two extreme positions and allowing only a rapid motion of the movable contact members from starting to running position, and automatic means for throwing 25 said switch from starting to running position.
13. In a motor starting switch having stationary starting and running contact members and coöperative movable contact members, and a cross head connecting said movable contact members, the combination of means controlling the sequence of operations of said switch, comprising a member directly engaging said cross head and automatic means for throwing said switch from starting to running position.
14. In a motor starting switch having stationary starting and running contact members and coöperating movable contact members and a cross head connecting said movable members, the combination of means controlling the sequence of operations of said switch, comprising a member directly engaging said cross head and allowing only a rapid motion of the movable contact members from starting to running position, and automatic means for throwing said switch from starting to running position.
15. In a motor starting switch having stationary starting and running contact members and coöperative movable contact members, and a cross head connecting said movable contact members, the combination of means controlling the sequence of operation of said switch and comprising a forked member surrounding said cross head in all positions and directly engaging said cross head, and automatic means for throwing said switch from starting to running position.
16. In a motor starting switch having stationary starting and running contact members and coöperating movable contact members, and a cross head connecting said movable contact members, the combination of means controlling the sequence of operation of said switch and allowing only a rapid motion of the movable contact members from starting to running position, comprising a forked member surrounding said cross head in all positions and directly engaging said cross head, and automatic means for throwing said switch from starting to running position.

ELECTRICAL SWITCH. Patent dated January 14, 1919. Disclaimer filed November 13, 1920, by the patentees and assignee, *Square D Company*.

Enters its disclaimer—

“To claims in said specification which read in the following words, to wit:

“8. In a motor starting switch having stationary starting and running contact members and coöperative movable contact members, the combination of means controlling the sequence of operations of said switch, and automatic means for quickly throwing said switch from starting to running position.

“9. In a motor starting switch having stationary starting and running contact members and coöperative movable contact members, the combination of means controlling the sequence of operations of said switch and allowing only a rapid motion of the movable contact members from starting to running position, and automatic means for quickly throwing said switch from starting to running position.

“10. In a motor starting switch having stationary starting and running contact members, the combination of means controlling the sequence of operations of said switch and allowing only a rapid motion of the movable contact members from starting to running position, comprising a one-piece spring tensioned member, and automatic means for quickly throwing said switch from starting to running position.

“13. In a motor starting switch having stationary starting and running contact members and coöperative movable contact members, and a cross head connecting said movable contact members, the combination of means controlling the sequence of operations of said switch, comprising a member directly engaging said cross head and automatic means for throwing said switch from starting to running position.

“14. In a motor starting switch having stationary starting and running contact members and coöperating movable contact members and a cross head connecting said movable members, the combination of means controlling the sequence of operations of said switch, comprising a member directly engaging said cross head and allowing only a rapid motion of the movable contact members from starting to running position, and automatic means for throwing said switch from starting to running position.”
